UNITED STATES PATENT OFFICE.

GERALD BASIL SYKES, OF CLECKHEATON, ENGLAND.

SPARKING PLUG FOR INTERNAL-COMBUSTION ENGINES.

Application filed June 14, 1921. Serial No. 477,580.

To all whom it may concern:

Be it known that I, GERALD BASIL SYKES, residing at St. John's House, St. John's Place, Cleckheaton, England, have invented new and useful Improvements in or Relating to Sparking Plugs for Internal-Combustion Engines, of which the following is a specification.

This invention has reference to sparking plugs of the type or kind in which earth or negative electrode or electrodes is or are in strip form and is or are inserted in a groove or grooves formed in the periphery of the insulating body of the plug and 10 clamped either directly between a circular projecting portion of the insulating body and a flat annular seating in the body of the plug or by a ring placed upon the seating and clamped in position by the said projection and a cap nut.

With the above named arrangements there is a danger of the earth or negative electrode or electrodes becoming detached from the insulating body and its or their supporting 25 ring and falling into the cylinder.

The object of this invention is to overcome the above difficulty by first forming the earth or negative electrode or electrodes separately and then securely fixing it or 30 them to the inner periphery of a metal ring at a suitable distance from its upper edge so that the metal ring is capable of being clamped in position between a tapering annular faced seating in the body of the plug 35 and the tapering face of a circular projection formed on a metal sleeve by a cap nut screwed on to the upper end of the body of the plug.

According to this invention the metal ring 40 to which the earth or negative electrode or electrodes is or are securely fixed is made of any required depth and of such a diameter that it will easily fit on to a metal sleeve and into a recess formed in the upper portion 45 of the body of the plug and rests upon a shoulder therein having a tapering face. The ends of the ring are correspondingly tapered to fit respectively against.—for forming a gas-tight joint,—the tapering 50 face of the circular projecting ring of the metal sleeve and the said seating.

Provision is made for either removing the positive electrode, insulating body and 55 wrappings and the sleeve forming one unit separately or together with the ring and its

electrode or electrodes forming another unit.

In the drawings hereunto annexed:—

Fig. 1 is an outside elevation of the sparking plug;

Fig. 2 a part vertical section of the same; 60

Fig. 3 a part sectional elevation of the central positive electrode, metal sleeve and insulating body;

Fig. 4 an elevation of the metal sleeve 65 with vertical groove cut therein;

Fig. 5 a plan of same looking at the top of Fig. 4;

Fig. 6 a plan looking at the lower end of Fig. 4;

Fig. 7 a sectional elevation of the retaining ring with the earth or negative electrode in position; 70

Fig. 8 a plan of the lower end of Fig. 7;

Fig. 9 an elevation of the retaining ring;

Fig. 10 a plan looking at the lower end 75 of Fig. 9.

All the views are drawn to an enlarged scale.

a is the usual casing or body of the plug provided with reduced and screw threaded 80 ends *b*, *c*, and with the central hole *d* having a shoulder with a tapering face *d*¹ therein. A cap nut *e* is mounted upon the upper screw-threaded portion *c*. The central positive electrode consists of a stem *f* 85 provided with an enlarged tapering end *f*¹. The upper end of the electrode is provided with the usual terminal screw *f*² and nut *f*³. On the stem of the central electrode *f* is mounted the insulating body consisting 90 of a sleeve made in two portions *g*, *g*¹. The insulating portions *g*, *g*¹ are each formed of a number of mica washers compressed together and afterwards turned to the shape shown in the drawings. A metal 95 sleeve *h* is also mounted upon the said stem and interposed between the mica portions *g*, *g*¹. The sleeve *h* is insulated from the stem *f* by two mica wrappings 1 and 2 of different lengths. 100

On the metal sleeve *h* is a circular projection *h*¹, the upper face of which is at or about a right angle to the insulating wrappings 1 and 2 whilst the under face of the projection *h*¹ is tapered at a suitable angle, 105 say, at or about thirty degrees. The insulating body *g*, *g*¹ is made of several diameters in its length, as shown at Figs. 2 and 3. The stem of the central positive electrode *f* is made to fit the central hole in the por- 110

tions of the insulating body g , g^1 and the mica wrappings 1 and 2. The upper portion g of the insulating body projects above the cap nut e and is tapered as shown at 5 Figs. 1 to 3, and on its upper end above the mica portion g there is a brass washer i , a brass nut j , a steel spring washer l and a lock nut k ; the just mentioned nuts being screwed upon the stem f , and they are employed for compressing the whole of the insulating body g , g^1 and retaining it in position on the stem f against the enlarged portion f^1 . The enlarged portion f^1 of the central positive electrode is made the same 10 diameter as the lower end of the portion g^1 of the insulating body, and the said enlarged portion f^1 projects a suitable distance below the reduced screw portion b of the body of the plug. One or more vertical 15 grooves m are formed in the peripheries of the sleeve h and upper part of the mica insulating portion g^1 for the reception of the earth or negative electrode or electrodes n . 20

25 The metal ring o is made of the same diameter as the circular projection h^1 of the metal sleeve h and to easily fit into the enlarged portion of the central hole d at the upper part of the body of the plug. The 30 ring o is made of any required depth and its upper edge is about level with the top of the screw-threaded portion c of the body of the plug. The central hole in the ring o is made of such a diameter that it will 35 easily fit on to the cylindrical parallel portion h^2 of the sleeve h . The upper and lower edges o^1 , o^2 of the ring o are arranged to taper towards the parallel portion h^2 of the sleeve h at or about an angle, say, 40 of thirty degrees so as to fit respectively against the tapering faces of the circular projection h^1 and shoulder or seating d^1 for forming gas tight joints. In the inner periphery of the ring o are formed one 45 or more transverse holes o^3 and one or more vertical grooves o^4 for the reception of the upper end n^1 of the earth or negative electrode n . The hole or holes o^3 are arranged

at a suitable distance from the upper end of the ring, as shown at Figs. 2, 7 and 9. 50 The end n^1 of the negative electrode n is turned at or about a right angle to the axis of the ring and the outer portion of the said end is riveted or otherwise suitably secured to the ring level with its outer periphery. The main pendant portion of the earth or negative electrode n projects a suitable distance into the central hole of the ring o so as to engage with, and easily slide in, the groove m , (Fig. 4), and the lower 55 end of the said electrode is inclined inwards towards the enlargement f^1 of the positive electrode at a similar angle.

By arranging the metal ring o ,—and negative electrode n attached thereto,—to 60 easily fit into the body of the plug it may be separately and readily removed after the positive electrode, the insulating body and wrappings and the metal sleeve forming the unit have been previously removed, or the 65 whole of the said parts may be readily removed together from the body of the plug for inspection, adjustment, cleaning, renewal and other purposes without there being any danger of the earth or negative electrode or electrodes n falling into the cylinder when the cap nut e and the positive electrode and parts connected therewith are withdrawn.

What I claim is:—

In a spark plug, the combination of a casing having a central hole and a tapering face therein, a positive electrode extending through said casing, an insulated metal sleeve having an annular projection and a 70 tapered lower surface encircling said positive electrode within the casing, a vertical groove in the periphery of said sleeve, a negative electrode extending within said groove, and a grooved ring having tapered 75 ends adapted to engage said sleeve and said negative electrode.

GERALD BASIL SYKES.
